CLAIM

The ornamental design for a surgeon instrument display screen with a graphical user interface of a robotic arm status indicator, as shown as described.

DESCRIPTION

The patent or application file contains at least one drawing executed in color. Copies of this patent or patent application publication with color drawing(s) will be provided by the Office upon request and payment of the necessary fee.

FIG. 1 is a front view of a surgeon instrument display screen with a graphical user interface of a robotic arm status indicator;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of a eighth embodiment thereof;

FIG. 9 is a front view of a ninth embodiment thereof; and,

FIG. 10 is a front view of a tenth embodiment thereof.

(Continued)

The broken lines showing the display screen form no part of the claimed design. The remaining broken lines showing portions of the graphical user interface form no part of the claimed design.
